RADIO DIRECTION FINDER

Peter C. Sandretto, Chicago, and Elmer P. Buckthal, Brookfield, Ill., assignors to United Air Lines, Inc., a corporation of Delaware

Application January 12, 1942, Serial No. 426,372

9 Claims. (Cl. 250—11)

1

The present application is a continuation in part of our copending application Serial No. 403,802, filed July 24, 1941, and entitled Radio direction finder.

The invention relates to control systems for radio direction finders, more particularly to direction finders of the type disclosed in our said copending application and control means therefor, and the invention has for an object the provision of reliable and accurately controlled direction finders of this character.

In various types of direction finders, and particularly those having relatively large rotating antenna means such as are disclosed in our said prior application, it is necessary or desirable that the antenna structure and the receiver unit be located in a relatively open area of large size which is free from power lines, metal fences, and similar structures which might influence the accuracy of the bearings received. It is also desirable that the necessity for an attendant at the site of the antenna structure be eliminated, and that the operator of the direction finder equipment be stationed in a readily accessible office or control station remote from the antenna site.

In receiving and recording the bearing records obtained through proper manipulation of the antenna structure and in controlling these manipulations, it is of course necessary to transmit between the antenna structure and the remote control station not only the incoming signals for producing the bearing record, but also a plurality of outgoing signals, and it is of course undesirable to utilize separate control wires for each control or bearing signal. Accordingly, it is a further object of this invention to provide an automatically controlled radio direction finder and a remote control system therefor, wherein a single transmission line is employed to carry the various control signals between the antenna site and the remote control station.

In carrying out the invention in one form, we provide at the antenna site or field station an antenna structure adapted to be selectively connected in a plurality of circuit arrangements to provide bearing signals of different character, means for controlling the circuit connections of the antenna structure, and a plurality of radio frequency receivers adapted selectively to be connected to the antenna structure. In addition, there is provided at the field station a source of relatively low signal frequency controlled by indexing means associated with the antenna structure, and a motor for suitably rotating the antenna structure at the desired speed. The vari-

2

ous output circuits from the radio frequency receivers and the source of low frequency signaling energy are arranged to be impressed on a single transmission line which leads to the control station. At the control station suitable selective filter means are provided for separating the various frequencies transmitted from the field station and conducting these separated frequencies to corresponding recording and indicating means.

- 5 10 15 20 25 30
- In addition, the control station is provided with a plurality of signal transmitting means for selectively imposing on the transmission line, signal frequency currents of either continuous or intermittent character for selectively controlling at the antenna site the operating motor, the antenna connections, and the respective radio frequency receivers so as to effect the desired operation of the direction finder system.

For a more complete understanding of the invention, reference should now be had to the drawings in which:

Figs. 1 and 2 are respectively the left- and right-hand sides of a single circuit diagram illustrating a remote control system and direction finder embodying the present invention;

Figs. 3 and 4 are, respectively, circuit diagrams illustrating the detailed circuit connections of the selector control and cardioid control means illustrated generally in Fig. 1; and

35 40 45 50

Fig. 5 is a diagrammatic illustration of one of the radio frequency receivers.

Referring now to the drawings, Fig. 1 illustrates somewhat diagrammatically the antenna structure and related equipment which comprise the field station located at the antenna site. The antenna structure is shown as comprising a pair of spaced apart shielded loop antennas 10 and 11, which are preferably, as described in our above referred to copending application, mounted in face-to-face relation on the opposite ends of a horizontally extending support or beam 12 which is carried on the upper end of a rotatable post 13 mounted on a suitable base 15 containing a driving motor and suitable gearing (not shown) for rotating the post and the antenna structure at a predetermined constant speed. Intermediate the loop antennas 10 and 11 is a vertical antenna 14 mounted on substantially the axis of rotation of the post 13.

55 As is more fully explained in our copending application, the loops 10 and 11 are intended selectively to be connected in opposed parallel relation with each other, so that either two or four nulls will be produced in the signal output of the receiver to which the loops are connected, de-

pending upon the characteristics of the propagating medium and the received radio wave, or one or both of the loops may be connected in circuit with the vertical antenna 14 so that the output signal of the receiver will follow the usual cardioid pattern for the purpose of indicating which of the previously referred to nulls represents the true bearing of the transmitting station.

In order to provide for such selective connection of the loops 10 and 11 and the antenna 14, a switching means, which is illustrated as a relay 16, is provided having a plurality of stationary contacts 17, 18, 19, 20, and 21, and co-operating movable contacts 22, 23, and 24. It will be observed that when the relay 16 is in the deenergized position shown in the drawings, the loops 10 and 11 will be connected in opposed parallel circuit relation with each other to a pair of conductors or bus bars 25 through the relay contacts 17, 22, 19, and 23. Upon energization of the relay 16, these contacts will open and the two loops 10 and 11 will be connected in additive parallel relation with each other to the conductors 25 through relay contacts 18, 22, 20, and 23, the vertical antenna at the same time being connected to a third bus bar 26 through the relay contacts 24 and 21. The manner in which the cardioid relay 16 is selectively energized, so as to produce a cardioid pattern during one revolution of the antenna structure and thereafter to connect the loops 10 and 11 in opposed parallel relation during subsequent revolutions, will be more fully described hereinafter.

Associated with the antenna structure and adapted selectively to be connected to the bus bars 25 and 26, are a plurality of radio frequency receivers 27 to 30, inclusive, each of which is tuned to one of the various frequencies on which the direction finder is to be used, suitable multiple pole switches 31 to 34 being provided for effecting the desired connection of the receivers to the bus bars. While four radio receivers are shown, it will of course be understood that any desired number may be provided, within the limits of the selector switch and the signaling means to be hereinafter described for selectively operating switches 31 to 34, inclusive.

While the radio frequency receivers may be of any desired type, they are preferably of the type described with particularity in our above referred to copending application, wherein a pair of beat oscillators are arranged to beat with the carrier of the signal frequency to provide a constant audio output beat note regardless of variations in the carrier frequency. In Fig. 5 the receiver 27 is shown somewhat diagrammatically as including a converter tube 101 having a plurality of control electrodes 102, 103 and 104, the control electrode 104 being supplied with the carrier frequency through the radio frequency stage (not shown) of the receiver, and the control electrodes 103 and 102 being respectively connected as shown to suitable crystal oscillators 35 and 36. The oscillators 35 and 36 are arranged to produce fixed frequencies having a frequency difference equal to the frequency which the band pass filter 54 (Fig. 2) is designed to pass.

For example, if the band pass filter is designed to pass a frequency of 1020 cycles plus or minus 30, the frequencies of the oscillators 35 and 36 will be so selected as to have a frequency difference equal to 1020 cycles. When the frequencies of the two crystal oscillators and the carrier are impressed on the control electrodes of the converter tube 101, two beat frequencies will be

generated equal respectively to the difference between the carrier frequency and the frequency of oscillator 35, and to the difference between the carrier frequency and the frequency of oscillator 36. These two beat frequencies pass through the intermediate frequency amplifier 37 which preferably is of the type having a wide response curve, and in the second detector contained in the detector and audio amplifier 38 these two intermediate frequencies beat together to form a beat note having a frequency equal to the difference between the fixed frequencies of the two oscillators.

It will of course be understood that similar oscillators having an identical frequency separation are associated with each of the radio frequency receivers 28, 29, and 30, as shown in Fig. 1. The arrangement is such that a constant beat note equal to the frequency separation of the two oscillators, which may be, for example, a frequency of 1020 cycles, will be produced at the output of the audio amplifier regardless of the respective frequencies of the carriers to which the various radio frequency receivers are tuned.

Also associated with the antenna structure at the field station is a suitable indexing means which, as shown in Fig. 1, comprises a cam operated switch 40 and an indexing relay 41 arranged to control the signal frequency supplied by a suitable oscillator 42. For purposes of illustration, the oscillator is indicated as being capable of generating a 120 cycle signaling frequency. As shown, the cam operated switch 40 includes a pair of contacts 43 arranged to control the energizing winding of the indexing relay 41 and an operating cam 44 which is carried by the post 13 so as to close the contacts 43 at a predetermined point during each revolution of the antenna structure. The indexing relay 41 is provided with two pairs of contacts 45 and 46, the contacts 45 being connected to control the oscillator 42 and the contacts 46 forming a part of suitable cardioid control means, indicated by the reference numeral 47, which will be more fully described hereinafter.

In addition to the above referred to elements, the field station equipment shown in Fig. 1 includes a suitable selector switch 48 for selectively controlling the switches 31 to 34, inclusive, a lock-out relay 48a, and suitable selector control means 49, which control means 49 is illustrated in detail in Fig. 3 and will be more fully described hereinafter. As shown, the selector switch 48, the lock-out relay 48a, and the output side of the detector and audio amplifier 38 are directly connected to one end of the transmission line 39, while the selector control means 49 and the 120 cycle oscillator are connected to the transmission line through the contacts of the lockout relay. While the single transmission line 39 may, of course, comprise two conductors, one conductor is all that is necessary, the return circuits being effected through the usual ground connections as indicated in the drawings.

At the control station, which is shown in Fig. 2, the transmission line 39 is connected to a second audio amplifier 51, and the output of this audio amplifier is connected to a plurality of suitable filter units 52, 53, 54, and 55. The filter unit 52 is a high pass filter unit, preferably capable of passing frequencies of 300 cycles and above, and is provided in order to insure the removal from this branch of the incoming circuits of all of the relatively low signaling and control frequencies. As shown, the filter units 53 and 54 are connected to the output of the filter unit 52, the filter unit

53 being adapted to reject the constant beat note frequency supplied to the transmission line by the audio amplifier 38. Thus the output of this filter 53 contains all of the audio components above 300 cycles except a small spectrum around 1020 cycles, and accordingly any voice frequencies present in a modulated carrier picked up by the antenna structure are transmitted through this filter unit 53 to a suitable loud speaker 56 which comprises a monitor channel. By means of this monitor channel the operator is able to identify the various signals received and may listen for directional bearing requests.

The band pass filter 54 is a highly selective filter adapted to pass frequencies having only a plus or minus variation of approximately 30 cycles from the beat note frequency supplied by the radio receivers to the transmission line. The high order of selectivity employed in this filter, which is preferably a 1020 cycle unit, enables the removal of substantially all static interference side bands. It has been found that even under severe static conditions, the beat note present at the output terminal of the filter 54 is substantially pure, and of course this beat note is present only when a carrier frequency is being received at the antenna station.

The band pass filter 55, which is connected in parallel with the filter unit 52, is adapted to pass the 120 cycle signal frequency placed on the transmission line by the oscillator 42, and it will thus be seen that the frequencies passing over the transmission line from the antenna site are separated into three distinct channels, one of which constitutes a 120 cycle indexing channel, the second of which constitutes a 1020 cycle directional signal channel, and the third of which constitutes an audio monitor channel.

In order that a continuous record of the signal intensity received at the antenna station and transmitted over the transmission line 39 may be produced at the control station of Fig. 2, recording means of the type disclosed in our above referred to copending application are provided at the control station. In Fig. 2 the recording means is shown as comprising a rotatable drum or recording surface 57 adapted to be driven through suitable reduction gearing (not shown) by a motor 58, the energization of which is controlled by a suitable motor starting switch 59. The motor for the recording means and the motor for the antenna structure are preferably of the synchronous type, and are energized from suitable 60 cycle sources of energy so that the recording drum 57 will be rotated in synchronism with the rotating antenna structure.

Associated with the recording drum is a tracing element or pen 60 adapted to be energized through a suitable rectifier 61 from the 1020 cycle channel containing the band pass filter 54, the recording pen 60 being preferably of the D'Arsonval type shown in our copending application, so that the pen, when energized, will trace on the recording surface 57 a continuous record of the signal intensity.

Also associated with the recording surface or drum 57 is an indexing pen or tracing element 62 adapted to be actuated by an energizing magnet 63 connected for energization through a suitable rectifier 64 from the 120 cycle signaling channel containing the band pass filter 55. Also energized from this 120 cycle channel is a suitable signal light 65 for indicating when the loops of the antenna structure are rotating, and a suitable control relay 66 which co-operates with the start-

ing switch 59 to control the energization of the recorder motor 58. In addition to the above described equipment, the control station shown in Fig. 2 includes a plurality of signal transmitting means 67, 68, and 69 adapted to be energized from a suitable source of 60 cycle energy, the transmitting means 68 and 69 being connected, as shown, to a suitable voltage divider 70 whereby the signal energy imposed on the transmission line by the devices 68 and 69 is at a reduced voltage comprising only a fraction of the signal energy voltage impressed by the device 67. All of the devices 67, 68 and 69 are connected by means of a conductor 71 to the transmission line 39.

The transmitting means 67 is of the type adapted to impress on a signaling circuit a selected number of short impulses for controlling the selector switch 48, the number of impulses determining the operation of the selector switch, and this transmitting means may constitute an ordinary telephone dial. The transmitting device 68 constitutes a push-button controlled pulsing relay arrangement adapted, when the push button is operated, to transmit a single pulse of predetermined duration. Such devices are of course well known in the art, and accordingly the details of the pulsing relay means have not been illustrated. The third transmitting device comprises 30 merely a manually operable double-pole single-throw switch adapted to be opened and closed, as desired, to impose on the signaling circuit a continuous 60 cycle signaling current and also to effect energization of the starting switch 59 for 35 the recorder motor 58.

With the above description of the component parts of the apparatus constituting the field station of Fig. 1 and the control station of Fig. 2, it is thought that a complete understanding of 40 our invention may now be had from a description of the operation required to obtain a bearing on any selected transmitting station, as, for example, a transmitter carried by an airplane in flight, the bearing of which, with reference to the field station, it is desired to determine.

The first control operation, in order to put the direction finder in condition for recording a bearing, is to start the loop rotating motor at the field station. This may be accomplished simply 50 by pressing the push button of the transmitting device 68 so as to impress on the transmission line 39, through the conductor 71, a measured pulse of 60 cycle energy at the previously referred to reduced voltage which is preferably less than one-half the full line voltage of the 60 cycle source and may be as low as two volts. The device 68 is so arranged that the pulse will be of a duration on the order of magnitude of one-tenth of a second, regardless of the length of time that the push button is held in its depressed position. At the field station end of the transmission line 39, this pulse of low voltage 60 cycle energy is transmitted through conductors 72 and 73, the contacts of the lockout relay 48a, and a conductor 73a to the selector control means 49, the details of which are illustrated diagrammatically in Fig. 3. Because of its low voltage this pulse will not effect operation of either the selector switch 48 or the lockout relay 48a.

As shown in Fig. 3, this selector control means 49 comprises a control relay 74 responsive to low voltage signal energy, which relay is connected for energization from the conductor 73a and includes a pair of normally closed contacts 75 and 76 a pair of normally open contacts 76. In addi-

tion, the device 49 comprises a slow-to-release relay 77 having two pairs of normally open contacts 78 and 79; a relay 80 which is both slow-to-operate and slow-to-release having normally closed contacts 81 and normally open contacts 82; and a ratchet type relay 83 which controls the energizing circuit for the motor in the antenna base 15. In order to provide for proper energization of the relays 77, 80, and 83, as well as the various other relays which are located at the field station, a suitable source of direct current energy is preferably provided which may be either a battery or a rectifier adapted to be energized from the source of energy supplying the antenna motor. For purposes of simplification, however, this source of direct current energy is indicated in the drawings by the conventional plus and minus signs, at 84 and 85 for example, and the source of energy itself is not shown.

The device 49 is adapted selectively to energize either the antenna motor circuit or the cardioid control means 47, depending upon whether a short pulse of low voltage energy is transmitted thereto from the transmitting device 68 or a continuous low voltage pulse is transmitted thereto from the transmitting switch 69. When a short pulse is received, as above described, the relay 74 is momentarily energized to close an energizing circuit for the relay 77, which energizing circuit may be traced from the positive side of the source of energy indicated by the reference numeral 84, through the energizing winding of the relay 77 and the contacts 76 of relay 74 to the negative side of the source of energy indicated at 85. Energization of the relay 77 effects closure of the contacts 78 and 79 thereof, and the contacts 79 establish an energizing circuit for the relay 80. This relay, however, being slow-to-operate, will not immediately operate, and accordingly an energizing circuit for the motor controlling ratchet type relay 83 is established which causes this relay to move forward one step and close the contacts thereof so as to connect the antenna motor to its 60 cycle source of energy through the conductors 86.

This energizing circuit for the ratchet type relay extends from the positive side of the source of energy indicated by the reference numeral 84, through conductor 84a, the winding of the relay 83, the contacts 81 of the relay 80, the contacts 78 of the relay 77 which remain closed due to the fact that the relay 77 is slow-to-release, through the contacts 75 of the relay 74, which has now returned to its deenergized position due to termination of the short pulse of signal energy, and thence to the negative side of the source of energy. The relays 77 and 80 are so related that the relay 77 will open before the relay 80 can close, and therefore operation of the relay 80 is not effected by a short pulse of signal energy.

Upon rotation of the antenna structure, the cam switch 40 is intermittently closed and opened to effect intermittent operation of the indexing relay 41, so that the contacts 45 thereof will intermittently close the circuit to the 120 cycle oscillator 42, and accordingly at each rotation a 120 cycle pulse of energy is imposed upon the transmission line 39. This 120 cycle impulse, as previously described, is filtered out at the control station end of the transmission line by means of the band pass filters 52 and 55, and is supplied to the operating winding 63 of the indexing pen 62, to the signal light 65 and to the relay 66. Intermittent operation of the relay 66, however, causes no control operation at this stage

due to the fact that the manual switch 69 is in its open circuit position. The signal lamp 65, however, flashes at recurrent intervals to indicate that the antenna loops are rotating.

The next step in obtaining a bearing reading at the control station is the selection of the particular frequency on which it is desired to take the bearing. This is accomplished simply by dialing the transmitting device 67 to send out over the transmission line 39 a series of line voltage impulses which will put into operation the receiver of the selected frequency. These impulses are transmitted at the field station end of the transmission line by way of the conductor 72a to the lockout relay 48a and by way of the conductors 72 and 87 to the selector switch 48, which may be of any well known type and which is adapted to set up circuit connections corresponding to the number of impulses received. This selector switch, for example, may be the usual Strowger type switch used in conventional automatic telephone systems, or may constitute a series of relays arranged to carry out a similar circuit connecting operation. The selector switch 48 operates to selectively energize one of the switches 31 to 34, inclusive, so as to connect the input of the desired one of the radio frequency receivers 27, 28, 29, or 30 to the bus bars 25 and 26 which lead from the antenna structure, as previously described, and simultaneously a suitable output control relay 105 in the selected receiver (Fig. 5) is energized. The line voltage impulse or impulses transmitted to the lockout relay 48a effect operation of this relay to interrupt the connection of the selector control means 49 to the transmission line. Thus, so long as these line voltage impulses are being sent out, the relay 74 of the selective control means 49 is disconnected from the transmission line and accordingly will not be energized by these impulses.

The operator may now listen to the loud speaker 56 connected to the monitor channel until he hears the signals on which the bearing is to be taken. If the operator at the transmitting station is talking, the operator of the direction finder will of course receive any requests for bearings or any other information that may be sent out over the transmitting station.

The system is now ready for the actual bearing taking operation, and the next step is merely to close the signaling device or switch 69 so as to impress on the transmission line, through the upper pole of said switch and the conductor 71, a continuous 60 cycle signal at the previously referred to low voltage. This continuous 60 cycle signal is transmitted, at the field station end of the transmission line 39, through the conductors 72 and 73, the contacts of the lockout relay 48a, and the conductor 73a to the selector control means 49, and again causes operation of the relay 74 to its energized position so as to close the contacts 76 thereof and effect closure of the relay 77. The previously referred to energizing circuit for the relay 80 is thus closed through the contacts 79 of the relay 77, and, since the relay 74 is now energized by a continuous 60 cycle current, the slow-to-operate relay 80 will operate to close its contacts 82 and apply energy to the cardioid control means 47 through the conductors 90. Operation of the ratchet type motor controlling relay 83 will not be effected by this continuous signal current, however, because the energizing circuit for the ratchet type relay is interrupted at the contacts 75 of the relay 74 and also at the contacts

81 of the relay 80 after this latter relay has operated.

The above-described application of power to the cardioid control means 47 conditions this control means 47 for operation by the contacts 46 of the indexing relay 41 under the control of the cam switch 40 carried by the rotating antenna structure. The details of the cardioid control means, which are fully described and claimed in our above-identified copending application, are shown in Fig. 4 and it will be seen that closure of the contacts 46 completes an energizing circuit for a control relay 106 having an energizing winding 107, two pairs of normally open contacts 108 and 109, respectively, and a pair of normally closed contacts 110. This circuit may be traced from the positive side of the source of energy represented by the conductors 90, through the conductors 111, 112, 113, and 114, the relay contacts 46, the conductor 115, the relay winding 107, and by way of a conductor 116 to the negative side of the source of energy. In order to simplify the drawings, the return connection to the negative side of the source of energy represented by the conductors 90 is not shown in full, but is indicated merely by a conventional minus sign.

In addition to the control relay 106, the cardioid control means 47 includes a plurality of control relays 117, 118, and 119, the energizing winding 120 of the relay 119 being connected in the output circuit of a full wave rectifier 121 having a pair of plates or anodes 122, a pair of cathodes 123, and a pair of control elements or grids 124. As shown, the grids or control elements 124 are adapted to be energized from a secondary winding 125 of a suitable coupling transformer, the primary winding 126 of which is connected by the conductors 100 to a suitable antenna for energization by the carriers of the transmitting stations to which the radio receivers are tuned. The primary winding 126 is preferably connected to the system of Fig. 1 at any suitable point so that it will be energized regardless of the one of the receivers 27 to 30, inclusive, which is selected and in operation, or the primary winding may, if desired, be connected to an entirely separate antenna and receiver. In order to provide a constant negative bias on the control elements 124 of the rectifier tube 121, the midpoint of the secondary winding 125 is connected to the negative side of the source of energy, as shown, and the cathodes 123 are connected to a suitable potentiometer represented as comprising resistance elements 127 connected across the direct current source of energy represented by the conductors 90.

Whenever carrier energy is being supplied to the rectifier tube through the transformer, current will flow through the winding 120 of the control relay 119 by way of a circuit which extends from the positive one of the conductors 90, through a conductor 128, the winding 120, the conductor 129, the anodes 122, the cathodes 123, and by way of a conductor 130 to the movable contact 131 on the potentiometer comprising the resistance elements 127.

As previously described, the operating motors of the antenna arrangement having been energized, the cam switch 40 operates to energize the indexing relay 41 and effect intermittent opening and closing of the contacts 46, and in describing the operation of the cardioid control means 47 it will be assumed that a carrier is being supplied to the winding 126 of the transformer so

as to effect operation of the relay 119. Upon closure of the contacts 132 of the relay 119, a condenser 133 will be discharged to effect energization of the relay 118, the condenser having previously been charged through a circuit which may be traced from the positive one of the conductors 90, through the conductor 129, a resistor 134, a conductor 135, and the condenser 133 to the negative one of the conductors 90 by way of a conductor 136. The energizing circuit for the relay 118, established by closure of the contacts 132, may be traced from one side of the condenser 133, through the conductor 135, the contacts 132, a conductor 137, the winding 138 of the relay 118, a conductor 139, the contacts 108 on the relay 106 which, as previously described, has been operated by closure of the contacts 46 on the indexing relay and by way of the conductor 116 to the negative one of the conductors 90 to which the opposite side of the condenser 133 is also connected by way of the conductor 136.

Following initial energization thereof, the relay 118 is held in its operated position by a holding circuit which may be traced from the positive one of the conductors 90, through the conductors 111, 112, and 140, contacts 109, conductor 141, contacts 142 on the relay 118, conductor 143, the winding 138 of the relay 118, conductor 139, contacts 108 and by way of the conductor 116 to the negative one of the conductors 90.

Closure of the contacts 144 of the relay 118 establishes an energizing circuit for the winding 145 of the relay 117, which circuit may be traced from the positive one of the conductors 90, through the conductors 111 and 146, the contacts 144, conductors 147 and 148, and by way of the winding 145 and a conductor 149 to the negative one of the conductors 90. The relay 117 is thus operated and the energizing circuits thus far traced continue to exist until the circuit is broken at the contacts 46 of the indexing relay, at which time the relay 106 is deenergized allowing contacts 108 and 109 to open and contacts 110 to close. Opening of the contacts 109 interrupts the previously traced holding circuit for the relay 118, and the consequent opening of the contacts 144 on this relay in turn interrupts the energizing circuit for the relay 117. Simultaneously, however, closure of the contacts 110 on the relay 106 provides a self-holding circuit for the relay 117 which may be traced from the positive one of the conductors 90 through the conductors 111, 112, and 140, contacts 110, a conductor 150, contacts 151 on the relay 117, conductors 152 and 148, and by way of the winding 145 and the conductor 149 to the negative one of the conductors 90. This transfer of the holding circuit for the relay 117 is accomplished without affecting the operated condition of the relay because this relay is of the slow-to-release type, as indicated diagrammatically in Fig. 4 by the usual copper slug 153a.

Operation of the relay 117 of course causes closure of the relay contacts 153, thereby completing an energizing circuit for the cardioid relay 16 which may be traced from the positive one of the conductors 90, through the conductors 111, 112, 113, and 154, the contacts 153 and by way of a conductor 155 to the operating winding of the relay 16, the opposite side of which is connected to the negative side of the source of energy as indicated by the ground connection shown in Fig. 1. As previously described, energization of the relay 16 is effective to connect

the loops 10 and 11 in additive parallel relation with each other to the conductors 25, and to connect the vertical antenna 14 to the conductor or bus bar 26. Thus during the first revolution of the antenna structure, the loop antennas and the vertical antenna will be connected in circuit so as to produce a directional or cardioid pattern which, as will be hereinafter described, is recorded on the recording surface 57 by the tracing element 60.

The previously described connections exist until the contacts 46 of the indexing relay 41 are again closed upon completion of one revolution of the antenna structure, whereupon the relay 106 will again be energized through the previously traced energizing circuit, causing the contacts 110 to open and interrupt the previously traced self-holding circuit for the relay 117. The capacity of the condenser 133 and the ohmic resistance of the resistor 134 are so chosen that between successive closures of the contacts 46 of the indexing relay 41 there will elapse an insufficient time to permit the accumulation on the condenser 133 of a charge of sufficient magnitude to effect operation of the relay 118. Therefore, even though the initial energizing circuit for the relay 118 is completed through the contacts of the relay 106 when this relay is again operated, the relay 118 will not operate and accordingly the relay 117 opens, thereby interrupting at contacts 153 the energizing circuit for the cardioid relay 16. Thus the relay 16 will return to the deenergized position shown in Fig. 1 and the loops 10 and 11 are connected in opposed parallel relation to the conductors or bus bars 25, as heretofore described. Due to the fact that the capacity and resistance values of the condenser 133 and the resistor 134 are chosen as indicated above, the operating cycle cannot be repeated until a sufficient time has elapsed to permit the condenser 133 to attain a new charge of sufficient magnitude to operate the relay 102.

After the desired record has been made in a manner to be further described hereinafter and the system has been allowed to rest for a relatively short time, operating voltage will build up across the condenser 133 and the above described cycle of operations may be repeated. Such an operating voltage, however, will not build up across the condenser until the system is thus allowed to rest because of the fact that the condenser is discharged each time that the contacts 108 of the relay 106 close.

It will now be apparent that as soon as energy is applied to the cardioid control, as heretofore described, the cardioid relay 16 is operated by the first closure of the cam switch 40 and remains closed until the next revolution of the antenna structure causes the energizing circuit for the relay 16 to be broken. The relay 16, therefore, returns to its deenergized position so as to connect the loops 10 and 11 in opposed parallel circuit relation and disconnect the vertical antenna 14, and the relay 16 will remain in this position during subsequent revolutions of the antenna structure. Furthermore, the carrier controlled interlock relay 103 which is energized through the conductors 109 insures that the above-described cycle of operations will take place only when a carrier is being received by the antenna structure.

Closure of the transmitting means or switch 69 to impose the above referred to continuous low voltage signaling current on the transmission line

39 is also effective through the lower pole thereof to prepare an energizing circuit for the recorder motor 58, so that the recorder motor will begin to operate as soon as a 120 cycle pulse is received over the transmission line. As shown in Fig. 2, this energizing circuit extends from the source of 60 cycle energy and the voltage divider 70, through the lower pole of the switch 69 and the conductor 91 to the energizing winding of the motor starting switch 59, and from this energizing winding the circuit is completed by the conductor 92 and the contacts of the relay 66 to the ground connection 93. Thus, as soon as the relay 66 closes, the motor starting switch 59 will be energized to close its contacts 94 and 95 and connect the motor 58 to its source of energy. Closure of the motor starting switch 59 also is effective through the contacts 96 thereof to establish a self-sealing circuit, so that the motor starting switch 59 remains energized after the relay 66 has opened and the motor 58 will therefore continue to operate until the switch 69 is manually opened after the bearing reading has been taken.

It will now be clear that, through the above-described cycle of control operations, the particular station on which a bearing is to be taken has been selected, the antenna structure has been started to rotate, and the recorder motor has been energized to drive the recording surface in synchronism with the rotating antenna structure. Therefore, there will be imposed on the field station end of the transmission line 39 a 1020 cycle note which varies in intensity in accordance with the directional characteristics of the radio wave picked up by the antenna structure. This 1020 cycle note passes through the amplifier 51, the filter units 52 and 54, and the rectifier 61 to the tracing element 60 which records on the recording surface 57 a trace of the signal intensity. At the same time, there is transmitted over the transmission line 39 a 120 cycle pulse of signal energy which causes the indexing pen or tracing element 62 to record on the chart a reference mark each time that the antenna structure passes through a predetermined compass position.

During the first revolution of the recorder, the conventional cardioid pattern will be traced thereon by the tracing element 60 in order to indicate the general sense or direction of the transmitting station, and on each succeeding revolution of the recording surface the tracing element 60 will impart to the recording surface a continuous trace of the 1020 cycle signal received with the loops 10 and 11 connected in opposed parallel circuit relation. The pen will of course retrace this path during successive revolutions if there has been no change in the signal intensity for identical positions of the antenna system. Variations in the propagating medium or in the signal energy received due to other disturbances will of course appear in the trace made by the pen 60, except in so far as they are eliminated by the antenna structure and its associated apparatus, and accordingly an average trace may readily be determined from the record produced.

The recording paper, or similar recording surface which is wrapped around the drum 58, may be graduated in degrees and, accordingly, the compass position of any maximum or minimum point in the continuous trace of the signal energy may readily be located by reference to the indexing mark formed on the recording paper or surface by the indexing pen or tracing element 62. The direction finder is preferably allowed to operate for a period of thirty seconds to one minute,

so that from seven to fifteen bearings will be obtained, the antenna structure preferably being rotated at a speed of approximately fifteen revolutions per minute, and the direction finder may then be shut down. To stop the recorder motor 52 in order to enable removal of the record paper from the recording surface 51, it is necessary only to open the switch 69 so as to interrupt the previously traced holding circuit for the motor starting switch 59. The operator may then remove the record paper and measure the distance from the index mark to the bearing null which is nearest to the cardioid bearing. This distance indicates in degrees the bearing of the transmitting station on which the bearing has been taken.

Upon opening of the switch 69, the relay 74 of the selector control means immediately returns to its deenergized position and opens the energizing circuit to the slow-to-release relay 71. The relay 71 then opens and deenergizes the relay 80 which is also slow-to-release and therefore will not effect closure of the contacts 81 for a short interval after opening of the contacts 78 on the relay 71 has occurred. The slow-to-release characteristics of the relay 80 insure that all of the relays 74, 71, and 80 will return to their respective deenergized positions without completing an energizing circuit for the ratchet relay 83 through the contacts 75, 78, and 81.

In order to stop the rotation of the antenna structure, it is necessary only to actuate the push button of the pulsing relay means 68 so as to transmit a short 60 cycle pulse of low voltage to the selector control means 49 so as to cause the relays 74, 71, and 80 to operate as hereinbefore described to energize ratchet relay 83. This energization causes the ratchet relay to move forward one step, whereupon the contacts of the ratchet relay open and interrupt the circuit to the antenna motor in the base 15. All of the parts having now returned to their initial positions, another bearing reading may be taken on any desired transmitting station merely by following again the above described procedure.

While we have shown particular embodiments of our invention, it will be understood, of course, that we do not wish to be limited thereto since many modifications may be made, and we, therefore, contemplate by the appended claims to cover any such modifications as fall within the true spirit and scope of our invention.

Having thus described our invention, what we claim and desire to secure by Letters Patent is:

1. In a radio direction finder system having an antenna station and a remotely located control station connected by a transmission line, the combination of rotatable directional antenna means at said antenna station, radio receiver means at said antenna station including a plurality of channels respectively tuned to receive signals of different preselected frequencies picked up by said antenna means, means at said control station for selectively imposing on said transmission line control signals of a predetermined frequency having preselected characteristics, means at said antenna station responsive to said control signals for selectively connecting between said transmission line and said antenna means a selected one of said channels of said receiver means corresponding to the selected signal characteristic, heterodyning means associated with said receiver means for imposing on said transmission line an output beat note of substantially constant frequency regardless of the selected receiver channel tuning, recording means at said control station energizable

75

to produce a record trace reflecting the intensity of the energizing signal, and filter means between said recording means and said transmission line for rendering said recording means responsive only to signals of said constant beat frequency, whereby a bearing trace of the received signal energy may be produced from any of said differently tuned receiver channels.

2. In a radio direction finder system having an antenna station and a remotely located control station connected by a transmission line, the combination of rotatable directional antenna means at said antenna station, radio receiver means at said antenna station including a plurality of channels respectively tuned to receive signals of different preselected frequencies picked up by said antenna means, means at said control station for selectively imposing on said transmission line control signals of a predetermined frequency having preselected characteristics, means at said antenna station responsive to said control signals for selectively connecting between said transmission line and said antenna means a selected one of said channels of said receiver means corresponding to the selected signal characteristic, heterodyning means associated with said receiver means for imposing on said transmission line an output beat note of substantially constant frequency regardless of the selected receiver channel tuning, indexing means at said antenna station for imposing on said transmission line indexing signals differing in frequency from said control signal frequency and said beat note frequency, said indexing signals reflecting the compass position of said antenna means, recording means at said control station having a plurality of energizable tracing elements, and filter means between said recording means and said transmission line for rendering one element of said recording means responsive only to said constant beat note frequency and another element thereof responsive only to said indexing signal frequency, whereby bearing traces of the signal energy received from said antenna means may be produced at said control station regardless of the frequency of the received signal and oriented with the compass position of said antenna means.

3. In a radio direction finder system having an antenna station and a remotely located control station connected by a transmission line, the combination of rotatable directional antenna means at said antenna station, radio receiver means at said antenna station including a plurality of channels respectively tuned to receive voice modulated signals of different preselected carrier frequencies picked up by said antenna means, means at said control station for selectively imposing on said transmission line control signals of a predetermined frequency having preselected characteristics, means at said antenna station responsive to said control signals for selectively connecting between said transmission line and said antenna means a selected one of said channels of said receiver means corresponding to the selected signal characteristic, heterodyning means associated with said receiving means for imposing on said transmission line the voice frequencies of said signals and a beat note of substantially constant frequency regardless of the selected receiver channel tuning, loud-speaker means at said control station, recording means at said control station energizable to produce a record trace reflecting the intensity of the energizing signal, and filter means connected to the control station end of said transmission line for rejecting from said

loud-speaker said control signal and said beat note frequencies and for rendering said recording means responsive only to signals of said beat note frequency, whereby a monitor channel is provided and a bearing trace of the received signal energy may be produced from any of said differently tuned receiver channels.

4. In a radio direction finder system having an antenna station and a remotely located control station connected by a transmission line, the combination of rotatable directional antenna means at said antenna station, radio receiver means at said antenna station including a plurality of channels respectively tuned to receive voice modulated signals of different preselected carrier frequencies picked up by said antenna means, means at said control station for selectively imposing on said transmission line control signals of a predetermined frequency having preselected characteristics, means at said antenna station responsive to said control signals for selectively connecting between said transmission line and said antenna means a selected one of said channels of said receiver means corresponding to the selected signal characteristic, heterodyning means associated with said receiver means for imposing on said transmission line the voice frequencies of said signals and a beat note of substantially constant frequency regardless of the selected receiver channel tuning, indexing means at said antenna station for imposing on said transmission line indexing signals differing in frequency from said control signal frequency and said beat note frequency, said indexing signals reflecting the compass position of said antenna means, recording means at said control station having a plurality of energizable tracing elements, monitor means at said control station responsive to voice frequencies, and filter means connected to the control station end of said transmission line for rejecting from said monitor means said indexing, signal and beat note frequencies, for rendering one element of said recording means responsive only to said beat note frequency and for rendering another element thereof responsive only to said indexing signal frequency, whereby signals picked up by said antenna means may be monitored and bearing traces of the signal energy received from said antenna means may be produced at said control station regardless of the frequency of the received signal and oriented with the compass position of said antenna means.

5. In a radio direction finder system having an antenna station and a remotely located control station connected by a transmission line, the combination of rotatable directional antenna means at said antenna station, radio receiver means at said antenna station including a plurality of channels respectively tuned to receive signals of different preselected frequencies picked up by said antenna means, means at said control station for selectively imposing on said transmission line control signals of a predetermined frequency having preselected characteristics, means at said antenna station responsive to said control signals for selectively connecting between said transmission line and said antenna means a selected one of said channels of said receiver means corresponding to the selected signal characteristic, heterodyning means associated with said receiver means for imposing on said transmission line an output beat note of substantially constant frequency regardless of the selected receiver channel tuning, motor means at said antenna station for rotating said antenna means,

means at said control station for imposing on said transmission line a second signal of the same control frequency but of different character than said signals of preselected characteristics, means at said antenna station responsive to said second control signal for energizing said motor means, indexing means for imposing on the antenna station end of said transmission line indexing signals differing in frequency from said control signal frequency and said beat note frequency and reflecting the compass position of said antenna means, recording means at said control station having a movable recording surface and a plurality of tracing elements, filter means at said control station for rendering one tracing element responsive only to said constant beat note frequency and another tracing element responsive only to said indexing signals, and means initially rendered effective by an indexing signal for driving said recording surface in synchronism with the rotation of said antenna means to produce at said control station a bearing trace of the signal energy received from said antenna means oriented with the compass position thereof regardless of the frequency of the received signal.

6. In a radio direction finder system having an antenna station and a remotely located control station connected by a transmission line, the combination of rotatable directional antenna means at said antenna station including a plurality of antenna elements adapted to be selectively connected in different circuit relations with each other, receiver means at said antenna station having an output circuit connected to said transmission line, indexing signal means controlled by rotation of said antenna for imposing on the antenna end of said transmission line signals of predetermined signal frequency, motor means for rotating said antenna, a plurality of control means at said antenna station for controlling said antenna circuit connections, for connecting said receiver means to said antenna means and for controlling said motor means, a source of signal frequency at said control station, signal means at said control station for selectively connecting said source to said transmission line to impose thereon signals of different characteristics separately to effect operation of said antenna control means, said receiver control means and said motor control means at said antenna station, and means at said control station jointly controlled by said indexing means and said receiver means at said antenna station and by said signal means at said control station for determining the compass bearing of radio frequency signals picked up by said antenna means during rotation thereof.

7. In a radio direction finder system having an antenna station and a remotely located control station connected by a transmission line, the combination of rotatable directional antenna means at said antenna station including a plurality of antenna elements adapted to be selectively connected in different circuit relations with each other, receiver means at said antenna station having an output circuit connected to said transmission line, indexing signal means controlled by rotation of said antenna for imposing on the antenna end of said transmission line signals of predetermined signal frequency, motor means for rotating said antenna, a plurality of control means at said antenna station for controlling said antenna circuit connections, for connecting said receiver means to said antenna means and for controlling said motor means, a source of signal

frequency at said control station, signal means at said control station for selectively connecting said source to said transmission line to impose thereon signals of different characteristics separately to effect operation of said antenna control means, said receiver control means and said motor control means at said antenna station, filter means at said control station for dividing into separate channels said indexing signal frequency and the output signal frequency of said receiver means transmitted over said transmission line and for rejecting from said channels the signal frequency of said source at said control station, and means at said control station energizable by said output signal frequency and said indexing signal frequency for recording a bearing trace of said output signal frequency during rotation of said antenna means and orienting said trace relative to the compass position of said antenna means.

8. In a radio direction finder system having an antenna station and a remotely located control station connected by a transmission line, the combination of rotatable directional antenna means at said antenna station including a plurality of antenna elements adapted to be selectively connected in different circuit relations with each other, receiver means at said antenna station having an output circuit connected to said transmission line for imposing thereon voice frequencies including a substantially constant beat note frequency, indexing signal means controlled by rotation of said antenna for imposing on the antenna end of said transmission line signals of predetermined frequency, motor means for rotating said antenna, a plurality of control means at said antenna station for controlling said antenna circuit connections, for connecting said receiver means to said antenna means and for controlling said motor means, a source of signal frequency at said control station, signal means at said control station for selectively connecting said source to said transmission line to impose thereon signals of different characteristics separately to effect operation of said antenna control means, said receiver control means and said motor control means at said antenna station, filter means at said control station for dividing into separate channels said indexing signal frequency, the output beat note frequency of said receiver means and the voice frequencies transmitted over said transmission line and for rejecting from said channels the signal frequency

of said source at said control station, monitor means connected to one of said channels for receiving said voice frequencies, and means at said control station energizable from said output beat note frequency channel and said indexing signal frequency channel for recording a bearing trace of said output signal frequency during rotation of said antenna means and orienting said trace relative to the compass position of said antenna means.

5 9. In a radio direction finder system having an antenna station and a remotely located control station connected by a transmission line, the combination of rotatable directional antenna means at said antenna station including a plurality of antenna elements adapted to be selectively connected in different circuit relations with each other, receiver means at said antenna station having an output circuit connected to said transmission line, indexing signal means controlled by rotation of said antenna for imposing on the antenna end of said transmission line signals of predetermined frequency, motor means for rotating said antenna, a plurality of control means at said antenna station for controlling said antenna circuit connections, for connecting said receiver means to said antenna means and for controlling said motor means, a source of signal frequency at said control station, signal means at said control station for selectively connecting said source to said transmission line to impose thereon signals of different characteristics separately to effect operation of said antenna control means, said receiver control means and said motor control means at said antenna station, recording means at said control station having a movable recording surface and a plurality of tracing elements, filter means at said control station for rendering one tracing element responsive only to the output signal frequency of said receiver and another tracing element responsive only to said indexing signal frequency, and means initially rendered effective by a signal of said indexing frequency for driving said recording surface in synchronism with the rotation of said antenna means to produce at said control station a bearing trace of said receiver output frequency during rotation of said antenna means and to orient said trace with the compass position of said antenna means.
